(57) **CLAIM**

The ornamental design for a garment, as shown and described.

DESCRIPTION

FIG. 1 is a top rear perspective view of a first embodiment of a garment showing my new design; FIG. 2 is a front view of the design shown of FIG. 1; FIG. 3 is a rear view of the design shown of FIG. 1; FIG. 4 is a left side view of the design shown of FIG. 1; FIG. 5 is a right side view of the design shown of FIG. 1; FIG. 6 is a top view of the design shown of FIG. 1; FIG. 7 is a bottom view of the design shown of FIG. 1; FIG. 8 is a top rear perspective view of a second embodiment of a garment showing my new design; FIG. 9 is a front view of the design shown of FIG. 8; FIG. 10 is a rear view of the design shown of FIG. 8; FIG. 11 is a left side view of the design shown of FIG. 8; FIG. 12 is a right side view of the design shown of FIG. 8; FIG. 13 is a top view of the design shown of FIG. 8; and, FIG. 14 is a bottom view of the design shown of FIG. 8. The evenly-spaced broken lines in the Figures illustrate portions of the garment that form no part of the claimed design. The short evenly dashed broken lines along the waistband of the garment depict claimed stitching. The dash-dot-dash broken lines in the figures illustrate the boundary of the claimed design which forms no part thereof.

1 Claim, 14 Drawing Sheets
